Primary Examiner — Nathan M Johnston(74) *Attorney, Agent, or Firm* — Bookoff McAndrews,
PLLC(57) **CLAIM**

The ornamental design for a drug-delivery device, as shown and described.

DESCRIPTION

FIG. 1 is a top, front, right perspective view of a drug-delivery device showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom view thereof.

The broken lines of even length shown in the drawings illustrate portions of the drug-delivery device that form no part of the claimed design.
